PNEUMATIC HYDRAULIC TRAVEL CONTROL
APPARATUS

Edward A. Rockwell, Cleveland, Ohio

Application June 4, 1943, Serial No. 489,711

17 Claims. (Cl. 60—54.5)

1

My invention relates particularly to an apparatus for controlling the movement of any desired part to be moved by power in such a way as to coordinate the travel of the control means and the part to be moved, although it is applicable particularly to the control of locomotive reverse gears.

The object of my invention is to provide an apparatus for moving any desired part to be moved by a control means in such manner that the travel of said part and the control means is coordinated so that by a given movement of the control means the same relative movement is obtained in the part to be moved. Another object is to provide a mechanism of this character in which the power applied for moving the said part is a pneumatic hydraulic mechanism. In other words, the said mechanism preferably comprises a hydraulic means for controlling the application of pneumatic power to the movement of said part. Another object is to provide a mechanism of the above character for moving the said part in opposite directions while maintaining the coordination of the movement thereof with that of the control means. Another object is to provide means for eliminating chattering and vibration in the manual control mechanism used in connection therewith. Further objects of my invention will appear from the detailed description of the same hereinafter.

While my invention is capable of being carried out in many different ways for the purpose of illustration I have shown only one form of my apparatus in the accompanying drawings in which the figure is a diagrammatic representation of an air-hydraulic travel controlling apparatus applied for controlling the operation of a locomotive reverse gear.

In the drawings I have shown a hand lever 1 carried on a pivot pin 2 to which it is fastened by a split ring 3 having a tightening screw 4. Within the hand lever 1 there is a helical spring 5 in a longitudinal recess 6, the upper end of which spring rests against a plunger pawl 7 which slides in the recess 6 but has a laterally directed tooth 8 projecting from a slot 9 in the side of the lever 1. A rod 10 is fastened to the upper end of the pawl 7 which is attached at its upper end to a manually operable plunger 11 extending out through the top of the hand lever 1. The laterally directed tooth 8 of the pawl 7 engages with an internal rack 12 on a segmental bracket 13 which is fastened on a lever housing 14 which carries the pivot pin 2. The hand lever 1 has a downwardly directed arm 15 carrying a roller 16,

2

within the lever housing 14, which bears against the lower side of a plug 17 in a hollow plunger 18 which is reciprocable within a cylindrical extension 19 on the lever housing 14. The hollow plunger 18 has an internal annular shoulder 20 to receive on its underface a head 21 of a subsidiary plunger 22 having around the same a spring 23 resting at its lower end against the shoulder 20 and its upper end against the underface of a master cylinder piston 24 formed on the subsidiary plunger 22. The said plunger 22 has an internal cylindrical chamber 25 which receives a valve rod 26 having a head 27 located below an internal annular flange 28 on the piston 24. Around the rod 26 and above the piston 24 there is provided a spring 29, the upper end of which is received beneath an apertured partition 30 within the cylindrical extension 19. The spring 29 normally forces the piston 24 downwardly and the spring 23 serves to prevent the transmission of vibrations from the controlling mechanism back to the hand lever 1. The said partition 30 has an opening 31 through which the valve rod 26 passes and openings 32 for the passage of hydraulic liquid in the apparatus, and which liquid may be of any desired character. On its upper end the valve rod 26 has a cylindrical valve member 33 beneath which there is located a coil spring 34 seating on the top of the partition 30. Furthermore, the said cylindrical valve member 33 has thereon a conical liquid compensating valve 35 which seats against a valve seat 36 in the top of the cylindrical extension 19 so as to control the passage of hydraulic liquid through a passage way 37 connected by a pipe 38 to the bottom of a hydraulic liquid reservoir 39 having lateral flanges 40 and holes 41 to support the reservoir in any desired manner. The said reservoir is equipped with a filling cap 42 having the usual vent aperture 43.

At the upper end of the cylindrical extension 19 there is, furthermore, provided an outlet opening 44 for the hydraulic fluid which may be discharged from the said cylindrical extension 19 by the manual pressure from the hand lever 1 through a pipe 45. The pipe 45 delivers the said hydraulic liquid to a pipe 46 and thence to a travel control cylinder 47 which is connected by an eye member 48 having a transverse aperture 49 to any desired fixed support. An air bleeder screw 50 is provided, normally closing the aperture 51 leading to the cylinder 47, by the removal of which from time to time the accumulated air can be discharged. Within the travel control cylinder 47 there is a plunger 53, one end of

which is connected to a piston 54 in a control cylinder 55 having a casing 56 which also forms a part of the casing for the cylinder 47 and on which the eye member 48 is located. At the two ends of the cylinder 55 there are provided air bleeder screws 57 and 58 similar to the air bleeder screw 50. Furthermore, the said piston 54 has attached thereto a plunger rod 59 having a pivotal connection 60 to a link 61 which in turn has a pivotal connection 62 to a bell crank lifting lever 63 carried on a lifting shaft 64 pivoted in a fixed bracket 65. The lifting bell crank lever 63 has an arm 66 for pivotal attachment to a lifting link 67 for lifting a radius rod 67a, the upper and lower positions of which, respectively, determine the forward or rearward drive of the locomotive, with any usual known form of locomotive reverse gear valve mechanism, such for example as those disclosed on pages 975 to 977 of Marks Mechanical Engineers Handbook, first edition, 1916, published by McGraw-Hill Book Company, Inc., New York. The piston 54 is adapted to be moved by power, by means of the supply and withdrawal of the hydraulic liquid under pressure through a pipe 68 entering the cylinder 55 at one side of the piston 54 and a pipe 69 entering the said cylinder at the other side of said piston. The pressure liquid supplied and withdrawn from the pipe 68 is obtained from the reservoir 39 by means of a pipe 70 supplying the liquid to a valve chamber 71 for liquid compensation, and which has a lateral port 72 connected to the pipe 68. The valve chamber 71 is located in a power unit 73 provided for moving the piston 54 towards the right. Likewise, the liquid received and discharged from the pipe 69 is obtained in a similar manner from a branch pipe 74 connected to the pipe 70 which in turn is connected to a liquid compensation valve chamber 75 in a power unit 76, for moving the piston 74 towards the left. The valve chamber 75 has a port 77 which connects it to the pipe 69.

The liquid supplied under manual pressure through the pipe 45 controls the operation of both the power units 73 and 76 by means of a branch pipe 78 connected to the said pipe 45. The pipe 78, accordingly, is connected to a plunger chamber 79 in the power unit 73 and which has a plunger 80 contacting with a valve plunger 81 to which there is attached a dished outlet valve 82 operating in a chamber 83 having air vents 84. The outlet valve 82 is adapted to seat on a diaphragm 85, of rubber or rubber-like material, the periphery of which is located in a fixed position in the power unit 73. The inner portion of the diaphragm 85 is carried by a valve sleeve member 86 which has a central longitudinal passageway 87 provided with a shoulder 88 supporting a helical spring 89, the upper end of which rests against a partition 90 in said unit 73 having air apertures 91. The sleeve member 86 is, furthermore, supported within a supporting diaphragm 92 of rubberized fabric, the periphery of which is fastened to the power unit 73. Furthermore, a plurality of inclined passageways 93 connect the chamber 87 with an annular chamber 94 located beneath a dished inlet valve 95 formed on the periphery of the valve member 86. Above the inlet valve 95 and between the two diaphragms 85 and 92 there is an air inlet chamber 96 which is connected to a compressed air supply pipe 97 leading to an air inlet chamber 98 in the power unit 76 which in turn is connected to a compressed air inlet pipe 99 supplied with air under any desired pressure, for example 100 to 150 lbs. per square inch. In

the power unit 73, furthermore, there is a main piston 100 operated by the compressed air when admitted through the apertures 91 and provided with a central stop 101 which engages with the partition 90 in the retracted position of the main piston 100. A coil spring 102 is supported at its lower end by the main piston 100 and at its upper end by the power unit 73 within a chamber 103, and within said chamber 103 there is, furthermore, provided a hollow pressure increasing plunger 104 having a central longitudinal chamber 105 to receive a valve rod 106 which passes through a hole 107 in the power increasing plunger 104, and which is provided with a head 108 within the chamber 105. A plurality of apertures 109 connect the chamber 105 with a pressure-increasing chamber 109a. A chamber 110 is connected by apertures 111 with the valve chamber 71, said apertures 111 being located in a partition 112 supporting a spring 113 at one end while the other end of said spring rests against a cylindrical valve member 114 having a conical valve 115 cooperating with a valve seat 116 in said power unit 73.

25 The said liquid under manual pressure received from the pipe 78 into the plunger chamber 79 is also conveyed by a pipe 117 to a plunger chamber 118 in the power unit 76 and having an air bleeder screw 119 like the air bleeder screws above referred to. In this instance the manual pressure liquid is received above a valve operating plunger 120, which is located above a coil spring 121 carried in an extension 122 of the said unit 76. It will be noted that while the plunger 100 in the power unit 73 is normally down so as to open the valve 82 and close the valve 95, the plunger valve operating plunger 120 is normally in the up position, due to the spring 121, until it is moved downwardly by the manual pressure liquid received through the pipe 117. This valve operating plunger 120 operates against a valve plunger 123 constructed the same as the valve plunger 81 in the power unit 73, the said plunger 123 serving to operate an outlet valve 124 and 45 an inlet valve 125 constructed the same as the corresponding valves 82 and 95 in the power unit 73. In fact, the other parts of the power unit 76 are constructed in the same manner as described in detail in connection with the power unit 73.

50 In the operation of the apparatus, when the hand lever 1 is moved into forward position, as shown in the drawing, the locomotive reverse gear is operated thereby so as to drive the locomotive forwardly, and when the hand lever 1 is moved downwardly to its lowermost position the said gear is operated to drive the locomotive rearwardly. Likewise, when the hand lever 1 is in its middle position on the segment 13 the said gear is in a position in which the locomotive is brought to rest. These positions of the hand operated lever for controlling the locomotive reverse gear are the usual positions provided for the manual operation of the locomotive reverse gear from the cab of a locomotive. Thus, for example, when the hand operated lever 1 is moved towards the forward position, as shown in the drawing, by the release and reengagement of the pawl 8 with the rack 12, it will be noted that the compressed air from the pipe 99 is being admitted to the interior of the power unit 76 and released from the power unit 73, thereby moving the main piston of said power unit 76 upwardly and the main piston in the power unit 73 downwardly and accordingly supplying the pressure liquid under intensified

pressure through the pipe 69 to the right side of the piston 54 and withdrawing the pressure liquid by the pipe 68 from the left side thereof. In any given position of the piston 54, a coordinate position is present in the hand lever 1 due to the travel control plunger 53 which is connected by the pipes 46 and 45 with the plunger 18 connected to the hand lever 1. Furthermore, in the downward position of either of the main pistons in the power units 73 and 76, respectively, 10 it will be noted that the respective liquid compensating valves 35 and 115 are open for readjustment of the liquid received from the reservoir 39. However, it will be noted that these liquid compensation valves are not open at the same time. Accordingly, each of said valves will compensate for the expansion and contraction, as well as leakage, in its particular hydraulic passages independently of the other. When the hand lever 1 is moved towards the central position on the segment 13 the piston 54 will be shifted towards its central position in the chamber 55 by the application of modulated amounts of the pressure liquid received in the left end of the cylinder 56 from the pipe 68 connected to the power unit 73, and by the modulating release of corresponding amounts of the pressure liquid from the right end of the chamber 55 through the pipe 69. These operations are accomplished by first the closing of the valve 82, and when closed the subsequent opening of the valve 95, and simultaneously a similar operation, in the reverse order, of the valves 124 and 125 in the power unit 76. However, due to the plunger 89 being moved forwardly hydraulically and the plunger 120 being moved forwardly by the spring 121 the valves connected thereto are capable of independent movement, and especially as said valves are subject to different pneumatic pressures, respectively, in the two cylinders 108 and as the two intensifying cylinders 110 have different liquid compensations. When the parts are at rest in any such intermediate position of the piston 54 the pneumatic valves of the two power units 73 and 76 will be in closed position. When the piston 54 is moved to the right end of the cylinder 56 by the movement of the hand lever 1 to its lowermost position on the segment 13 the locomotive is being driven in the rearward direction. In the left end position of the piston 54 it will be understood that the compensating valve 35 will be in open position.

Thus, the locomotive reverse gear will be shifted in either direction by the application of power applied in modulated amounts in either direction of movement thereof, and with the desired amount of power being applied thereto to relieve the manual force required in operating the shifting mechanism accordingly. This mode of operation of the locomotive reverse gear will, furthermore, eliminate the hysteresis and hunting in the same due to the fact that the piston 54 is held in any given position by the high pressure liquid operating against the opposite sides of the said piston. However, to eliminate the transmission of all appreciable vibratory effects from the reverse gear to the hand lever 1 the spring 23 has been introduced, which is carried on the subsidiary piston member 22 having a lost motion connection with the manual operating plunger 18. The spring 23 is provided, also, for the purpose of yielding in case of the backing up of the liquid, to avoid breakages. In this way, the manual lever 1 will be smooth in operation and can be shifted with little or no effort to bring

about the changes in position of the reverse gear by gradual transition from one position to another and without the transmission of any vibrations, chattering or hysteresis from the reverse gear mechanism to the manually operated lever 1.

While I have described my invention above in detail I wish it to be understood that many changes may be made therein without departing from the spirit of the same.

I claim:

1. In combination, a part adapted to be moved, a cylinder having a hydraulically operated piston connected thereto, and hydraulic means for applying liquid under pressure to opposite sides of the hydraulic piston having a liquid pressure producing means connected to one side of the piston and a separate liquid pressure producing means connected to the other side of the piston so as to apply the pressure liquid to one side thereof and coordinately release pressure liquid from the other side thereof, including compressed air power units, having cylinders and compressed air pistons fitting therein, said compressed air pistons having connected thereto liquid pressure producing plungers as well as hydraulic compensation valves provided with a common source of supply, and hydraulic controlling means operable at will, having a hydraulic connection and valve mechanism connected thereto, for controlling the operation of the compressed air pistons of said power units to apply pressure simultaneously to the liquid on both sides of the hydraulic piston or to apply pressure to one side of the hydraulic piston while releasing liquid from the other side to cause movement of the hydraulic piston, said hydraulic controlling means having a hydraulic compensation valve leading to said source.

2. In combination, a part adapted to be moved, a cylinder having a hydraulically operated piston connected thereto, and hydraulic means for applying liquid under pressure to opposite sides of the hydraulic piston having a liquid pressure producing means connected to one side of the piston and a separate liquid pressure producing means connected to the other side of the piston so as to apply the pressure liquid to one side thereof and coordinately release pressure liquid from the other side thereof, including compressed air power units, having cylinders and compressed air pistons fitting therein, said compressed air pistons having connected thereto liquid pressure producing plungers as well as hydraulic compensation valves provided with a common source of supply, hydraulic controlling means operable at will, having a hydraulic connection and valve mechanism connected thereto, for controlling the operation of the compressed air pistons of said power units to apply pressure simultaneously to the liquid on both sides of the hydraulic piston or to apply pressure to one side of the hydraulic piston while releasing liquid from the other side to cause movement of the hydraulic piston, said hydraulic controlling means having a hydraulic compensation valve leading to said source.

3. In combination, a part adapted to be moved, a cylinder having a hydraulically operated piston connected thereto, hydraulic means comprising a plurality of power units, for applying liquid under pressure to opposite sides of the hydraulic piston so as to apply the pressure liquid to one side thereof and coordinately release pressure

liquid from the other side thereof, each of said power units having inlet and outlet air valves as well as an air piston and a power intensifying hydraulic plunger each of said power units having as well a liquid compensation valve operatively attached to the air piston, and a single hydraulic means, having a liquid compensation valve in hydraulic communication with said other plurality of liquid compensation valves, for simultaneously controlling the position of inlet and outlet air valves of said power units.

4. In combination, a part adapted to be moved, a cylinder having a hydraulically operated piston connected thereto, and hydraulic means for applying liquid under pressure to opposite sides of the hydraulic piston having a liquid pressure producing means connected to one side of the piston and a separate liquid pressure producing means connected to the other side of the piston so as to apply the pressure liquid to one side thereof and coordinately release pressure liquid from the other side thereof, including compressed air power units, having cylinders and compressed air pistons fitting therein, said compressed air pistons having connected thereto liquid pressure producing plungers as well as hydraulic compensation valves provided with a common source of supply and hydraulic controlling means operable at will, having a hydraulic connection for controlling the operation of the compressed air pistons of said power units to apply pressure simultaneously to the liquid on both sides of the hydraulic piston or to apply pressure to one side of the hydraulic piston while releasing liquid from the other side to cause movement of the hydraulic piston, said hydraulic controlling means having a hydraulic compensation valve leading to said source, each of said units having inlet and outlet air valves operatively connected to the hydraulic connection as well as a power intensifying hydraulic plunger attached to the compressed air piston.

5. In combination, a part adapted to be moved, a cylinder having a hydraulically operated piston connected thereto, and hydraulic means for applying liquid under pressure to opposite sides of the hydraulic piston having a liquid pressure producing means connected to one side of the piston and a separate liquid pressure producing means connected to the other side of the piston so as to apply the pressure liquid to one side thereof and coordinately release pressure liquid from the other side thereof, including compressed air power units, having cylinders and compressed air pistons fitting therein, said compressed air pistons having connected thereto liquid pressure producing plungers as well as hydraulic compensation valves provided with a common source of supply, hydraulic controlling means operable at will, having a hydraulic connection, for controlling the operation of the compressed air pistons of said power units to apply pressure simultaneously to the liquid on both sides of the hydraulic piston or to apply pressure to one side of the hydraulic piston while releasing liquid from the other side to cause movement of the hydraulic piston, said hydraulic controlling means having a hydraulic compensation valve leading to said source, and a hydraulic travel coordinating plunger operable with said hydraulic piston having a hydraulic connection with the hydraulic controlling means, each of said power units having inlet and outlet air valves operatively connected to the hydraulic connection as well as

a power intensifying hydraulic plunger attached to the air piston.

6. In combination, a part adapted to be moved, a cylinder having a hydraulically operated piston connected thereto, and hydraulic means for applying liquid under pressure to opposite sides of the hydraulic piston having a liquid pressure producing means connected to one side of the piston and a separate liquid pressure producing means connected to the other side of the piston so as to apply the pressure liquid to one side thereof and coordinately release pressure liquid from the other side thereof, including compressed air power units, having cylinders and compressed air pistons fitting therein, said compressed air pistons having connected thereto liquid pressure producing plungers and hydraulic controlling means operable at will, having a hydraulic connection, for controlling the operation of the compressed air pistons of said power units to apply pressure simultaneously to the liquid on both sides of the hydraulic piston or to apply pressure to one side of the hydraulic piston while releasing liquid from the other side to cause movement of the hydraulic piston, each of said power units having air inlet and outlet valves operatively connected to the hydraulic connection and one of said power units having a hydraulic plunger for closing the outlet valve and the other power unit having a spring-pressed hydraulically releasable plunger normally closing the outlet valve.

7. In combination, a part adapted to be moved, a cylinder having a hydraulically operated piston connected thereto, and hydraulic means for applying liquid under pressure to opposite sides of the hydraulic piston having a liquid pressure producing means connected to one side of the piston and a separate liquid pressure producing means connected to the other side of the piston so as to apply the pressure liquid to one side thereof and coordinately release pressure liquid from the other side thereof, including compressed air power units, having cylinders and compressed air pistons fitting therein, said compressed air pistons having connected thereto liquid pressure producing plungers, hydraulic controlling means operable at will, having a hydraulic connection, for controlling the operation of the compressed air pistons of said power units to apply pressure simultaneously to the liquid on both sides of the hydraulic piston or to apply pressure to one side of the hydraulic piston while releasing liquid from the other side to cause movement of the hydraulic piston, and a hydraulic travel coordinating plunger operable with said hydraulic piston having a hydraulic connection with the hydraulic controlling means, each of said power units having air inlet and outlet valves operatively connected to the hydraulic connection and one of said power units having a hydraulic plunger for closing the outlet valve and the other power unit having a spring-pressed hydraulically releasable plunger normally closing the outlet valve.

8. In combination, a part adapted to be moved, a cylinder having a hydraulically operated piston connected thereto, and hydraulic means for applying liquid under pressure to opposite sides of the hydraulic piston having a liquid pressure producing means connected to one side of the piston and a separate liquid pressure producing means connected to the other side of the piston so as to apply the pressure liquid to one side thereof and coordinately release pressure liquid from the other side thereof, including compressed air power units, having cylinders and compressed air pistons

fitting therein, said compressed air pistons having connected thereto liquid pressure producing plungers as well as hydraulic compensation valves provided with a common source of supply and hydraulic controlling means operable at will, having a hydraulic connection for controlling the operation of the compressed air pistons of said power unit to apply pressure simultaneously to the liquid on both sides of the hydraulic piston or to apply pressure to one side of the hydraulic piston while releasing liquid from the other side to cause movement of the hydraulic piston, said hydraulic controlling means having a hydraulic compensation valve leading to said source, each of said power units having inlet and outlet air valves operatively connected to the hydraulic connection as well as a power intensifying plunger attached to the compressed air piston, the power intensifying plungers having liquid compensating valves adapted to open in the retracted positions of the air pistons.

9. In combination, a part adapted to be moved, a cylinder having a hydraulically operated piston connected thereto, and hydraulic means for applying liquid under pressure to opposite sides of the hydraulic piston having a liquid pressure producing means connected to one side of the piston and a separate liquid pressure producing means connected to the other side of the piston so as to apply the pressure liquid to one side thereof and coordinately release pressure liquid from the other side thereof, including compressed air power units, having cylinders and compressed air pistons fitting therein, said compressed air pistons having connected thereto liquid pressure producing plungers as well as hydraulic compensation valves provided with a common source of supply and hydraulic controlling means operable at will, having a hydraulic connection for controlling the operation of the compressed air pistons of said power units to apply pressure simultaneously to the liquid on both sides of the hydraulic piston or to apply pressure to one side of the hydraulic piston while releasing liquid from the other side to cause movement of the hydraulic piston, said hydraulic means having a hydraulic compensation valve leading to said source, and a hydraulic travel coordinating plunger operable with said hydraulic piston having a hydraulic connection with the hydraulic controlling means, each of said power units having inlet and outlet air valves operatively connected to the hydraulic connection as well as a power intensifying plunger attached to the compressed air piston, the power intensifying plungers having liquid compensating valves adapted to open in the retracted positions of the air pistons.

10. In combination, a part adapted to be moved, a cylinder having a hydraulic piston connected thereto, and hydraulic means for applying liquid under pressure to opposite sides of the hydraulic piston so as to apply the pressure liquid to one side thereof and coordinately release pressure liquid from the other side thereof, including compressed air power units, having movable walls responsive to movement by the compressed air, adapted to simultaneously apply the pressure from compressed air to the pressure liquid on both sides of the hydraulic piston and hydraulic controlling means, including a valve mechanism for admitting compressed air to said units, operable at will for controlling the operation of said power units, said controlling means having a manual lever provided with a rack and pawl and with a master cylinder provided with a piston and hav-

ing a plunger operable by the manual lever and a spring interposed between the master cylinder piston and the plunger.

11. In combination, a part adapted to be moved, a cylinder having a hydraulic piston connected thereto, and hydraulic means for applying liquid under pressure to opposite sides of the hydraulic piston so as to apply the pressure liquid to one side thereof and coordinately release pressure liquid from the other side thereof, including compressed air power units, having movable walls responsive to movement by the compressed air, adapted to simultaneously apply the pressure from compressed air to the pressure liquid on both sides of the hydraulic piston, hydraulic controlling means, including a valve mechanism for admitting compressed air to said units, operable at will for controlling the operation of said power units, and a hydraulic travel coordinating plunger operable with said piston having a hydraulic connection with the hydraulic controlling means, said controlling means having a manual lever provided with a rack and pawl and with a master cylinder provided with a piston and having a plunger operable by the manual lever and a spring interposed between the master cylinder piston and the plunger.

12. In combination, a part to be moved, means for applying a varying degree of hydraulic pressure, a source of air pressure controlled thereby, fluid pressure operated hydraulic pressure developing apparatus, including two movable walls and a pair of movable liquid compensating valves responsive to said air pressure as well as a valve mechanism having two valves controlling the access of the air pressure to said walls respectively, and independently operable valve actuating plungers operated by said hydraulic pressure, said valves being constructed to receive the air pressure and apply to said part, by the action of one of said plungers against a previous bias of one of said valves, a hydraulic pressure which decreases coordinately as the first mentioned hydraulic pressure increases.

13. In combination, a part to be moved, means for applying a varying degree of hydraulic pressure, a source of air pressure controlled thereby, fluid pressure operated hydraulic pressure developing apparatus, including two movable walls and a pair of movable liquid compensating valves responsive to said air pressure as well as a valve mechanism having two valves controlling the access of the air pressure to said walls, respectively, and independently operable valve actuating plungers operated by said hydraulic pressure, said valves being constructed to receive the air pressure and apply to said part, by the action of one of said plungers against a previous bias of one of said valves, a hydraulic pressure which decreases coordinately as the first mentioned hydraulic pressure increases, so as to move said part in one direction, and by the action of another one of said plungers a hydraulic pressure for moving said part hydraulically in the opposite direction, one of said two valves being connected to said source of air pressure for supplying a hydraulic pressure which increases as said first mentioned hydraulic pressure increases.

14. In combination, a part to be moved, means for applying a varying degree of hydraulic pressure, a source of air pressure controlled thereby, fluid pressure operated hydraulic pressure developing apparatus, including two movable walls and a pair of movable liquid compensating valves responsive to said air pressure as well as a valve

mechanism having two valves controlling the access of the air pressure to said walls respectively, and independently operable valve actuating plungers operated by said hydraulic pressure, having on each movable wall a pressure increasing piston connected thereto, as well as a cylinder for the piston, said valves being constructed to receive the air pressure and apply to said part, by the action of one of said plungers against a previous bias of one of said valves, a hydraulic pressure which decreases coordinately as the first mentioned hydraulic pressure increases.

15. In combination, a part to be moved, means for applying a varying degree of hydraulic pressure, a source of air pressure controlled thereby, fluid pressure operated hydraulic pressure developing apparatus, including two movable walls and a pair of movable liquid compensating valves responsive to said air pressure as well as a valve mechanism having two valves controlling the access of the air pressure to said walls respectively, and independently operable valve actuating plungers operated by said hydraulic pressure, having on each movable wall a pressure increasing piston connected thereto, as well as a cylinder for the piston, said valves being constructed to receive the air pressure and apply to said part, by the action of the said plungers against a previous bias of one of said valves, a hydraulic pressure which decreases coordinately as the first mentioned hydraulic pressure increases, so as to move said part in one direction, and by the action of another one of said plungers a hydraulic pressure for moving said part hydraulically in the opposite direction, comprising a valve device having a pressure increasing piston connected thereto, as well as a cylinder for the piston, one of said two valves being connected to said source of air pressure for supplying a hydraulic pressure which increases as said first mentioned hydraulic pressure increases.

16. In combination, a part to be moved, means for applying a varying degree of hydraulic pressure, a source of air pressure controlled thereby, fluid pressure operated apparatus including a valve mechanism, said apparatus having a plunger and pressure increasing piston connected thereto, as well as cylinders for the plunger and piston, constructed to receive the air pressure and apply a hydraulic pressure so as to move said part in one direction, and a fluid pressure operated device, including a valve mechanism, having a plunger and pressure increasing piston connected

thereto, as well as cylinders for the plunger and piston, constructed to receive the air pressure and deliver a hydraulic pressure so as to move said part in the opposite direction, the valve mechanism of said apparatus and the valve mechanism of said device being connected together hydraulically for respective hydraulic self-adjustment independently of each other.

17. In combination, a part to be moved, means for applying a varying degree of hydraulic pressure, a source of fluid pressure differing from the atmospheric pressure, controlled thereby, fluid pressure operated apparatus, including a valve mechanism, constructed to receive the said fluid pressure and apply a hydraulic pressure so as to move said part in one direction, and a fluid pressure operated device, including a valve mechanism, constructed to receive the said fluid pressure and deliver a hydraulic pressure so as to move said part in the opposite direction, the valve mechanism of said apparatus and the valve mechanism of said device being connected together hydraulically for respective hydraulic self-adjustment independently of each other.
